WITNESS:

UNITED STATES PATENT OFFICE.

PALMER H. GARDNER, OF CRYSTAL SPRINGS, MISSISSIPPI.

TRAY ATTACHMENT.

Application filed March 24, 1923. Serial No. 627,401.

To all whom it may concern:

Be it known that I, PALMER H. GARDNER, a citizen of the United States, residing at Crystal Springs, in the county of Copiah, and State of Mississippi, have invented new and useful Improvements in Tray Attachments, of which the following is a specification.

This invention contemplates the provision of a new article of manufacture in the nature of a paper weight primarily intended for use in conjunction with letter baskets or trays, although its general use and application is contemplated by the claims.

In carrying out the invention, I provide a paper weight of novel construction preferably formed from a single length of wire and adapted to be wholly arranged within the receptacle with which it is used, the weight proper being associated with means which pivotally supports the weight upon one wall of the receptacle.

Another object of the invention resides in providing an article of the above mentioned character wherein the opposed sides of the weight are suitably connected together by a support or bracing member adapted to contain advertising matter, so that the article is also particularly advantageous as an advertising medium.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a perspective view showing the application of the article to a receptacle.

Figure 2 is a view of the article removed from the receptacle.

Figure 3 is a sectional view taken on the line 3—3 of Figure 2.

The article forming the subject matter of the present invention includes the member A herein above referred to as the weight, and which member is preferably constructed from a single length of wire and given the configuration or outline shown, although this may be varied without departing from the spirit of the invention. However, as

shown in this particular instance, a length of wire forming the member A is shaped to provide a substantially triangular shaped portion of a size consistent with the size of the particular receptacle with which it is used, it being borne in mind that the invention in addition to being used in connection with paper and letter baskets or the like can be used in money drawers, or in fact receptacles and compartments of any size or shape. The sides 10 of this triangular portion are twisted together as at 11, and the wire and material is then continued to provide spaced limbs 12 which terminate to provide eyes or loops 13. These loops 13 accommodate themselves to a member utilized to pivotally support the weight upon one end wall of the receptacle as shown in Figure 1. The sides 10 of the triangular shaped portion are connected together and braced by a suitable frame 14, and this frame is designed to receive a member 15 having an outline of the same configuration as the frame and which member is adapted to bear advertising matter. Consequently the device is not only useful as a paper weight but is also meritorious in the capacity of an advertising medium.

Any suitable means may be employed for pivotally supporting the weight upon one wall of the receptacle, but in order to produce a complete article which can be manufactured and sold at a very nominal cost, I provide a member for this purpose which is also constructed from a single length of wire. This member is indicated at B, and is formed with an intermediate V-shaped portion 16 which lies between spaced substantially U-shaped portions 17, the outermost limbs of each U-shaped portion being extended inwardly to form the V-shaped intermediate portion as shown. The innermost or adjacent limbs of the U-shaped portions terminate to provide loops 18 which are associated with the eyes 13 formed by the terminals of the weight above described. This connection permits the weight to have pivotal movement so that it can be arranged at any height or angle within the receptacle when in use. Of course, the supporting member just described is easily attached to the wall of the receptacle, by arranging the intermediate V-shaped portion 16 at one side of the wall with the U-shaped portions of course against the opposite sides thereof,

the article in its entirety can be conveniently attached to any receptacle or removed therefrom when desired.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. A paper weight for receptacles comprising in combination a clamp designed to straddle one wall of the receptacle, a weighted member constructed from a single length of material and formed to provide an enlarged end portion substantially triangular in plan, and spaced limbs projecting from the apex of said end portion, said limbs being twisted at the point of juncture with the limbs of said end portion, the free

ends of said limbs being pivotally associated with the clamp in a manner whereby the weighted member is wholly disposed within the receptacle. 25

2. A paper weight adapted for use with receptacles and comprising in combination a clamp designed to accommodate itself to one wall of the receptacle, a weighted member constructed from a single length of wire and formed to provide an enlarged end portion of substantially triangular formation in plan, and spaced limbs, said limbs being 30 twisted together at a point adjacent the apex of said end portion, and terminating to provide eyes for pivotal connection with said clamp, and a reinforcing plate disposed within the confines of said enlarged end portion and corresponding in shape therewith, and said plate being connected with the opposed sides of said end portion. 35

In testimony whereof I affix my signature.

PALMER H. GARDNER.
